UNITED STATES PATENT OFFICE.

GEORGE A. JONES, OF BALDWIN, NEW YORK, ASSIGNOR TO ORDNANCE ENGINEERING CORPORATION, OF NEW YORK, N. Y., A CORPORATION OF NEW YORK.

ADJUSTABLE LINER FOR TYPE-CASTING MACHINES.

1,340,831.

Specification of Letters Patent.

Patented May 18, 1920.

Application filed February 15, 1919. Serial No. 277,124.

To all whom it may concern:

Be it known that I, GEORGE A. JONES, a citizen of the United States of America, residing at Baldwin, Long Island, in the 5 county of Nassau and State of New York, have invented certain new and useful Improvements in Adjustable Liners for Type-Casting Machines, of which the following is a specification.

10 This invention relates to liners for molds of type-casting machines, and also to certain combinations of said liners with other parts of type-casting machines and aims to provide improvements therein.

15 In the casting of slugs for type or lines of type, it is necessary to adjust the height of the mold space for slugs of different "point" or height, and also to adjust the width of the mold space for each different 20 width of slugs (corresponding to different widths of column) to be set up. In order to simplify the description, however, the invention will be hereinafter particularly described with reference to use in the casting 25 of slugs for lines of type.

The height of the mold space is usually adjusted by substituting liners of different height, that is, by substituting a different liner for each "point" of type used. And 30 the width of the mold space is usually adjusted by substituting one of the liners (of a pair) for another of similar height but of different length, depending on the width of the mold space corresponding to the 35 width of column desired.

Therefore, to provide a type-casting machine with a mold space adjustable to the various height or "point" of type, and to the various column widths met with in actual 40 practice, requires the owner of a type-casting machine to keep on hand a very large number of liners, which liners are relatively costly.

The present invention provides a liner 45 which takes the place of a number of liners, and which is usable in modern machines, with all the advantages of present liners. The present invention reduces, to a very large extent, the number of liners heretofore 50 necessary in order to adjust a mold space to its full capacity as to height and width of the slugs cast therein, as two, at most, of the present adjustable liners will take the place of 51 ordinary liners in a 30 em mold.

The invention further provides a liner 55 which may be placed in position and removed with minimum effort.

An embodiment of the invention is illustrated in the accompanying drawings.

In said drawings:

Figure 1 illustrates the front of a mold, as usually constructed.

Fig. 2 is a top plan view of an adjustable liner embodying the present invention.

Fig. 3 is a rear elevation of the liner shown 65 in Fig. 2.

Fig. 4 is a sectional view of the liner shown in Fig. 2.

Fig. 5 is a view similar to Fig. 2 of another form of liner embodying the invention. 70

Fig. 6 is a sectional view of the liner shown in Fig. 5.

Fig. 7 is a top plan view of a liner used opposite the adjustable liner.

Referring to the drawings, A designates a 75 mold, such as usually employed in type-casting machines. This mold is shown as mounted upon a rotatable mold disk, but it is not essential that the mold be so mounted.

The mold usually comprises a mold base 80 B, a mold cap C, and liners D and E, the liners D and E being clamped against the base by latches F, F, which draw the parts together.

The liner E preferably occupies a definite 85 position at one side of the mold, the liner, for this end, being conveniently provided with holes e^1 , e^2 , in which fit short pins or studs e^3 , e^4 , projecting from the cap C and base B, respectively. The liner E is also 90 usually provided with a notch e^5 , through which the latch F passes.

The liner E is placed opposite the liner D, and the space formed between these liners constitutes the mold space in which 95 the slug is cast, the face e^6 of the liner E, and the face e^7 of the liner D forming the sides of the mold space, the front e^8 of the mold space being closed during the casting of the slug by a line of matrices, and the rear e^9 of the mold space being closed by the lip or face of the pot containing the type metal, which pot is moved into contact with the rear of the mold prior to casting the slug, and from which pot the metal 100 is forced for casting the slug, the said lip or face of the metal pot being usually provided with a series of small orifices, the

series having a width corresponding to the maximum width of the mold space as indicated at p , p .

Referring particularly to Figs. 2 to 6, inclusive, the adjustable liner forming the subject of the present invention, and designated by reference letter D, is most conveniently formed in two parts d ; d^2 . The part d is adapted to occupy a fixed position in the mold, and the part d^2 is movable with reference to the part d , in such manner as to vary the width of the mold space.

For fixing the position of the part d it is conveniently formed with a hole or recess d^4 adapted to fit a pin or stud d^5 projecting from the mold base B. The part d is also conveniently formed with a recess d^6 through which the latch F passes.

The part d^2 is provided at its rear side with a longitudinally extending part d^7 , which part d^7 has a rear face d^8 which is adapted to cover and shut off the flow of metal from all of the orifices of the pot which are not opposite the mold space between the faces d^3 and e^7 of the liners D and E. The part d^7 and its face d^8 , are also of sufficient length to entirely cover all of said orifices in the lip or face of the pot (except those between the faces d^3 and e^7 of the mold space), when the part d^2 is adjusted inwardly to provide a minimum width of mold space within the limits of adjustment of the liner. As will be explained hereinafter, it is not always possible to provide for all of the adjustments of width of the mold space with a single adjustable liner, but the whole range of adjustments of width of the mold space can usually be provided for with two adjustable liners. If the working parts of the machine admit of it, there is no reason why a single adjustable liner cannot be made to take care of all the adjustments of width of the mold space of the machine. The face d^9 of the extension d^7 , and the face d^{10} of the part d^2 conveniently form a guide for the part d^2 in its adjustments in the mold.

Preferably the part d^2 has a longitudinally extending part d^{12} at the front of the liner, corresponding to the longitudinally extending part d^7 . These two longitudinally extending parts d^7 and d^{12} preferably fit closely the faces d^9 and d^{13} of the part d , so that a good guiding effect of the part d^2 on the part d is obtained. There is also preferably a rib and slot connection d^{15} , d^{16} , between the parts d and the extensions d^7 , d^{12} of the part d^2 , though the liner may be made with other forms of connection, or even without connections.

In order that the liner d may be firmly clamped in the mold between the base B and the cap C, it is preferably tapered at one of its upper or lower faces, from its inner to its outer end, viz., the width de-

creasing from the face d^3 to the opposite end. This same effect might, without departing from the invention, be accomplished by appropriately tapering one or the other of the faces of the cap or mold base which bear upon the latter.

Where it is desired to provide for adjustments of extreme width of the mold space, the adjustable liner D is conveniently formed as indicated in Figs. 5 and 6. Referring to the construction shown in said Figs. 5 and 6, the part d^2 near its inner end, is conveniently recessed, as indicated at d^{18} , and the end of the part d is also correspondingly recessed upon its upper face, as indicated at d^{19} , and the positioning hole or recess d^4 is formed in this portion d^{19} of the part d . This construction enables the parts d and d^2 to telescope to the maximum extent, and also preserves the strength of the parts.

In order to conveniently determine the exact width of the mold space, and also to conveniently carry out adjustments, the relatively movable parts d and d^2 are provided one with a datum mark and the other with suitable graduations, as for example, ems of type. Moreover, a plurality of datum lines may be provided on principles of a vernier, whereby extremely accurate adjustments may be made.

Operation: In casting slugs of any particular width, in order to change the machine for casting slugs of another width, it is simply necessary to loosen or remove the mold cap and move the part d^2 inward or outward with relation to the part d , to the desired extent, thereby adjusting the width of the mold space between the faces d^3 , e^7 , of the liners D and E. The mold cap is thereupon tightened or replaced, and the mold is ready for having cast therein slugs of the new width. The extension d^7 serves to shut off all of the perforations p in the face or lip of the pot containing the molten type metal, which are not opposite the space in the mold between the faces d^3 , e^7 of the liner, and thereby prevents any part of the mold or liner being fouled by metal from the pot which is not necessary for casting the slug.

After the slug is cast, it is, as usual, separated from the metal in the pot, shaved or trimmed and ejected.

It is obvious that the inventive ideas herein set forth may receive other mechanical expressions than those herein specifically illustrated and described.

What is claimed is:

1. A liner for the mold of a type-casting machine, comprising parts adjustable as to length, one part having a face at the side which goes at the rear of the mold of a length sufficient to shut off all the part of the duct or ducts from the casting pot ex-

cept those opposite the open space in the mold wherein the type or linotype is to be cast, in all positions of adjustment of said liner.

5 2. A liner for the mold of a type-casting machine, comprising a part adapted to be fixed in a definite position on one side of the mold and a part slidable thereon, said slid-
10 able part having a face at the rear side of the liner of greater length than said fixed part, said rear face of said slidable part lapping said fixed part, whereby the rear of said liner may present a continuous face to the part of the casting pot opposite the liner.

15 3. A liner for the mold of a type-casting machine, comprising a part adapted to be fixed in a definite position on one side of the mold and a part slidable thereon, said slid-
20 able part having a face at the rear side of the liner of greater length than said fixed part, said rear face of said slidable part lapping said fixed part, whereby the rear of said liner may present a continuous face to the part of the casting pot opposite the liner, said fixed part having a latching notch thereon, and also a positioning recess thereon.

25 4. A liner for the mold of a type-casting machine, comprising a part adapted to be fixed in a definite position on one side of the mold and a part slidable thereon, said slid-
30 able part having a face at the rear side of the liner of greater length than said fixed part, said rear face of said slidable part lapping said fixed part, whereby the rear of said liner may present a continuous face to the part of the casting pot opposite the liner, said two parts having between them graduations and a datum line indicating the
35 proper adjustments for a mold space of various widths.

40 5. A liner for the mold of a type-casting machine, comprising a part adapted to be fixed in a definite position on one side of the mold and a part slidable thereon, said slid-
45 able part having a face at the rear side of the liner of greater length than said fixed part, said rear face of said slidable part lapping said fixed part, whereby the rear of said liner may present a continuous face to the part of the casting pot opposite the liner, said two parts being of equal height.

45 6. A liner for the mold of a type-casting machine, comprising a part adapted to be fixed in a definite position on one side of the mold and a part slidable thereon, said slid-
55 able part having a face at one side of greater length than said fixed part, said liner being slightly tapered from its end which faces the mold space to its other end.

60 7. A liner for the mold of a type-casting

machine, comprising a part adapted to be fixed in a definite position on one side of the mold and a part slidable thereon, said slid-
65 able part having a face at one side of greater length than said fixed part, said fixed part having its inner end reduced in thickness and said slidable part having its inner end correspondingly recessed, whereby said reduced parts overlap in certain positions of
70 adjustment of said part.

8. A liner for the mold of a type-casting machine, comprising a part adapted to be fixed in a definite position on one side of the mold and a part slidable thereon, said 75 slidable part having a face at one side of greater length than said fixed part, said fixed part having its inner end reduced in thickness and said slidable part having its inner end correspondingly recessed, where-
80 by said reduced parts overlap in certain positions of adjustment of said part, the reduction of said fixed part being effected by removing metal from the upper face of said part and a positioning recess formed in said 85 reduced portion of said fixed part of the liner.

9. The combination, in a type-casting machine, of a mold, a metal pot having an orifice or series of orifices, having a length 90 corresponding to the maximum width of mold space in said mold, and an adjustable liner comprising a fixed and a movable part, adapted to adjust the width of said mold space, said liner having a rear face adapted 95 in all of its adjusted positions to stop or close that part of the orifice or series which is not opposite the mold space when the pot is in casting position.

10. In a type-casting machine, a mold 100 comprising a base, a cap and an adjustable liner, two of said parts of the mold having a face between them which is slightly tapered longitudinally of the mold, whereby the adjustable part of the liner may be 105 firmly fastened in place when the mold parts are fastened together.

11. A liner for the mold of a type-casting machine comprising a part adapted to be fixed in a definite position on one side of the mold, and a part slidable thereon, said 110 slidable part having extensions adapted to embrace said fixed part, one of said extensions being of a length to extend beyond said fixed part in certain positions of adjustment of said parts, and adapted to shut off all parts of the orifice in a pot from the end of the liner to one end of the orifice.

In witness whereof I have hereunto signed my name.

GEORGE A. JONES.
